UNITED STATES PATENT OFFICE.

CHARLES H. FOGG, OF HYDE PARK, MASSACHUSETTS, ASSIGNOR TO JAMES W. BROOKS, PRINCIPAL TRUSTEE, AND JOHN BROOKS, ASSOCIATE TRUSTEE.

BLANK-FEEDING DEVICE.

SPECIFICATION forming part of Letters Patent No. 629,441, dated July 25, 1899.

Application filed October 22, 1896. Serial No. 609,695. (No model.)

To all whom it may concern:

Be it known that I, CHARLES H. FOGG, a citizen of the United States, residing at Hyde Park, in the county of Norfolk and State of Massachusetts, have invented a new and useful Improvement in Blank-Feeding Devices, of which the following is a full, clear, and exact specification, reference being had to the accompanying drawings, forming a part of this specification, in explaining its nature.

My invention relates to the improvement in blank-feeding devices hereinafter described. It is represented as applied to the top-lift-feeding mechanism of a heel-attaching machine.

Referring to the drawings, Figure 1 is a view in vertical section and in elevation of parts of a machine to which the invention is applied. Fig. 2 is a view of the same parts, showing the cam as having made a portion of a revolution and the top-lift-feeding plate as arrested by a top lift. Fig. 3 represents in plan, enlarged, the top-lift centering and receiving devices and the top-lift-feeding plate, the parts being in the position which they occupied preparatory to the feeding of the top lift to the top-lift holder and receiver. The same figure also shows upon the dotted lines the top-lift holder and receiver as having received a top lift and as having been transferred from the position represented by full lines to the attaching position. Fig. 4 is a view in plan representing the relation of the top-lift-feeding plate to the top-lift receiver and holder at the end of the feeding movement. Fig. 5 is an enlarged view, in horizontal section, upon the dotted line 5 5 of Fig. 1.

I have represented the invention as applied to a heel-attaching machine, but desire it to be understood that I do not confine it to that use. In such machines it is desirable to automatically feed a portion of a heel, known as the "top lift," from the under side of a pile or stack of lifts held in a box to a receiver which receives and holds centered the blank (and transfers it, if desired) during the operation of spanking it or upon attaching it to the remainder of the heel. The receiver and spanker-plate, to which it is attached, are

represented in Figs. 3 and 4, where A is the spanker-plate; B B', the receiving-arms; b, the spring for closing them and holding them closed, and C the back-stop, which for top lifts preferably has the V-shaped end c. These 55 parts need not further be described.

D is the top-lift feeder. It has the abutment d, preferably formed at the end of a separate plate d', rigidly secured to the plate D. The plate is adapted to be moved at 60 any desired interval upon a slideway in the bracket D', and it and its abutment are adapted to coöperate together in feeding a blank from the stack D². It is reciprocated by means of the lever E, pivoted at e, the link F, the 65 cam-groove g in the crank-wheel G, and the lever H, pivoted at h and having the cam-pin h' to enter the cam-groove and connected at its upper end h² with the said link F.

I have spoken of the connection between 70 the upper end of the lever H and the lever E as a link. It is not made, however, in one piece, but is constructed so as to be extensible. This result is obtained by making the link in two parts f f', the ends of which overlap, and these parts are yieldingly connected with each other by means of a spring interposed between their ends. The two parts are connected in a manner to permit one to 75 slide upon the other in one direction in opposition to the stress of the spring. I prefer that the parts be connected with each other and with the spring in the following manner:

The part f has at its end an eye f², the shank of which extends laterally through a slot f³ 85 in the part f', and this eye provides a support for one end of a rod f⁵, the opposite end of which is held in an ear extending upward from the end f', and this rod carries the coiled spring f⁶, the ends of which are confined between the ear f⁴ and the eye f², the eye being free to move on the rod f⁵. This spring is of sufficient tension to maintain the entire link of a uniform length during its ordinary or normal operation; but in case the blank-feeder meets with obstruction which stops its feed the section f' of the link may then draw upon the section f, compressing the spring f⁶ between the ear f⁴, which moves with the section f', and the eye of the section f, which 90 95 100

does not move, so that all the movement of the operating cam or device is taken up by the spring, and injury to the blank-feeder and parts closely related thereto is prevented.

5 It will be understood that this spring also acts at the end of the feeding movement of the feeding-plate to cause the abutment to straighten, square, or center the blank in the receiver—that is, upon moving the blank into 10 the receiver and into contact with the back-stop it comes to a rest, while the section f' of the link continues to move, thereby bringing spring tension upon the abutment. The entire feeder then comes to rest with a yielding 15 pressure upon it. The section f of the link may be united to the section f' by a pin f^7 thereon, which projects laterally into the guiding-slot f^8 in the link-section f' .

It will be understood that the feeding-plate 20 has a long movement and that it is desirable that the extensible link be connected with its operating-lever E near its fulcrum end or where its movement is relatively slight, because by so doing less movement is required 25 of the spring in its take-up motion, and a better form of spring can therefore be used. While I have illustrated the extensible link as operated by the cam g and the lever H , I would not be understood as limiting myself 30 to these means of operating the feed-plate through the extensible link.

In use the blank is fed by the feeding-plate to the blank-receiver, when the abutment acts as a centering or straightening device in connection with the remainder of the receiver or parts thereof. If, however, there is any obstruction, such as a previously-fed blank, in the receiver or a tipped blank in the stack, the feeding movement of the blank-feeding 35 plate is automatically stopped without injury to it or any of its operating parts, and upon removal of the obstruction the feeding 40 may be resumed as before.

Having thus fully described my invention, 45 I claim and desire to secure by Letters Patent of the United States—

1. The combination of the blank-receiver, the blank-feeder having a rigid abutment which acts as a centering or straightening device in connection with the receiver, and 50 means for exerting a yielding pressure upon

the abutment and feeder at the end of their feeding movement, substantially as described.

2. The combination of a receiver comprising the arms B , B' and the back-stop C with 55 the blank-feeder having the abutment d , the plate A carrying the receiver and means for moving the blank-holding plate and abutment convertible into a yielding force upon the contact of the blank with the back of the receiver 60 and the abutment with the blank, substantially as and for the purposes described.

3. In a machine for automatically feeding heel and similar blanks, the combination of 65 a blank-receiver adapted to receive and hold a blank fed to it with a blank-feeding device and means for moving the blank-feeding device to feed a blank to the receiver, which means is adapted to exert a yielding pressing force upon the blank following the end of the 70 feeding movement, whereby the blank is first fed and then centered as and for the purposes described.

4. In a machine of the character specified, 75 the combination of an inverted blank receiving, holding and feeding device, a blank-feeding plate having a shoulder or abutment upon it, and means for moving said feeding-plate and abutment beneath the blank receiver and holder, which means are adapted to yield because of obstruction in the path of the blank or its feeding-plate, and at the end of the feeding movement, as and for the purposes 80 set forth.

5. The combination in a machine of the 85 character specified, of the carrier A , means for holding a blank by its edges attached to said carrier, a blank-feeding plate D having a shoulder or abutment thereon and mounted in a guideway, a lever E connected with said 90 plate to operate the same, a cam g , a lever H , one end of which is operated by the cam and a connection between the said lever H and the lever E comprising the sectional link F , one part of which is adapted to be movable 95 in relation to the other, and the interposed resistance-spring f^6 , as and for the purposes set forth.

CHAS. H. FOGG.
